UNITED STATES PATENT OFFICE.

WILLIAM MESSERLE, OF CINCINNATI, OHIO, ASSIGNOR OF ONE-HALF TO
JOSEPH AUTE, OF SAME PLACE.

BUSHING-MOLD.

SPECIFICATION forming part of Letters Patent No. 359,735, dated March 22, 1887.

Application filed January 17, 1887. Serial No. 234,517. (No model.)

To all whom it may concern:

Be it known that I, WILLIAM MESSERLE, a citizen of the United States, residing at Cincinnati, in the county of Hamilton, State of Ohio, have invented certain new and useful 5 Improvements in Bushing-Molds, of which the following is a specification, reference being had therein to the accompanying drawings.

My invention comprises a peculiar construction of mold that enables the expeditious casting of those soft-metal bushings which are screwed into the faucet-holes of beer-kegs and other similar vessels containing liquor "on tap." Said mold consists of a laterally-divided two-part flask, a bottom plate upon 15 which said flask is centered, and a mandrel that occupies an axial position within the matrix and imparts the desired tapering bore to the bushing, as hereinafter more fully described.

In the annexed drawings, Figure 1 is a plan of the bottom plate of my mold. Fig. 2 is a side elevation of the mandrel thereof. Fig. 3 is a plan of the upper side of the two-part flask in its open position. Fig. 4 is a plan of the under side of said flask in its closed position. Fig. 5 is a plan of the complete mold with the mandrel inserted therein. Fig. 6 is a vertical section of the complete mold taken 30 at the line *zz* of the preceding illustration. Fig. 7 is a front elevation of the closed flask detached from the bottom plate, the lower portion of said flask being sectioned. Fig. 8 is an axial section of a bushing that has been 35 cast in the mold and then detached therefrom.

Referring to Figs. 1 and 6, A represents the bottom plate of my mold, which plate has an elevated annular flange or curb, B, a circular pit, C, a concentric bore or socket, D, and a 40 pair of diametrically-opposite pins or stumps, E E'.

F and G represent the two parts of my flask, said flask being hinged together at H and having handles f g, wherewith it is readily operated. Furthermore, these sections of the 45 mold have respectively semi-cylindrical bores I J, opening into the sloping tops K L of the matrix M M', which latter is screw-threaded, as seen in Fig. 6.

N is the gate or pouring-channel of the flask 50 F, said flask being provided with a pin, o, over which is engaged the free end of a hook or latch, O, said hook being pivoted to the other flask, G.

P P' represent shallow semi-cylindrical 55 counterbores in the lower ends of the flasks F G.

R is a cylindrical mandrel, having a conical portion, S, and shank T.

My mold is used in the following manner: 60 The plate A is first placed horizontally upon a table or bench, and shank T of mandrel R is then inserted in the bore or socket D of said plate, the cone S of said mandrel resting upon the bottom of pit C, as seen in Fig. 6. The 65 flask F G is then set upon said plate A, so as to cause the upper portion, R, of the mandrel to occupy the now cylindrical bore I J of the flask, the latter being centered upon said plate by the curb or flange B entering the cylindrical counterbore P P'. The soft metal is then poured in at the gate N, and fills up the matrix, (shown in Fig. 6,) and after the metal is sufficiently cool or hardened the latch O is unhooked from the pin o and the two parts 70 of the flask, F and G, are opened laterally, thus liberating the mold from the casting. The casting is then lifted out of the bottom plate and the mandrel is knocked out of the bushing, thereby producing the device seen in Fig. 80 75 8. Reference to this illustration shows that the bushing has an annular rim, e, that was formed in the circular pit C, and the rim has a pair of sockets, e e', produced by the pins E E'. Furthermore, said bushing has an 85 external thread, m, that was formed in the internal screw, M M', of the matrix, and a conical end, l, to which the sprue or jet n is attached, which sprue is subsequently broken off the casting. The bushing can then be 90 readily screwed into the proper hole in the head of a keg or barrel, the sockets e e' enabling the convenient use of a spanner for this purpose. A cork is then driven into the conical opening s of said bushing, and when the 95 keg is tapped the cork is forced into the keg, and said opening is then occupied by the faucet-heel, in the usual manner. Finally, dowel-

pins or other devices may be used, instead of the latch O, for locking the flask in its closed position.

I claim as my invention—

5 A mold for casting soft-metal screw-threaded bushings for the faucet-holes of beer-kegs, &c., which mold consists of the bottom plate, A, having a curb, B, pit C, socket D, and pins E E', and the hinged flasks F G H, provided
10 with semi-cylindrical bores I J, threaded ma-

trix M M', gate N, and counterbores P P', in combination with the detachable mandrel R, having a conical portion, S, and shank T, substantially as described.

In testimony whereof I affix my signature in presence of two witnesses.

WILLIAM MESSERLE
